Primary Examiner — Angela J Lee(74) *Attorney, Agent, or Firm* — Pearne & Gordon LLP**CLAIM**

The ornamental design for a taillight, as shown and described.

DESCRIPTION

FIG. 1 is a perspective view of my new invention;

FIG. 2 is a front view thereof;

FIG. 3 is a left side view thereof;

FIG. 4 is a top view thereof;

FIG. 5 is a bottom view thereof;

FIG. 6 is a right side view thereof; and,

FIG. 7 is a rear view thereof.

The broken lines shown in the drawings illustrate portions of the taillight that form no part of the claimed design.
